EDGAR A. WHITAKER, OF PROVIDENCE, RHODE ISLAND, ASSIGNOR TO CHARLES N. RICHARDSON, OF PROVIDENCE, RHODE ISLAND.

AERIAL-LADDER TRUCK.

1,256,964.

Specification of Letters Patent. Patented Feb. 19, 1918.

Application filed August 17, 1916. Serial No. 115,492.

To all whom it may concern:

Be it known that I, EDGAR A. WHITAKER, a citizen of the United States, residing at Providence, in the county of Providence, State of Rhode Island, have invented certain new and useful Improvements in Aerial-Ladder Trucks, of which the following is a specification.

My invention relates to aerial-ladder trucks and consists of an improved mechanism for controlling the operation of the ladder-elevating means. The object of my improvement is to provide a manually-controlled device for positively locking the ladder in its lowered position, and also for securing it against movement when raised on the truck.

The manner and means for carrying out the improvement are fully described in the following specification, illustrated by the accompanying drawings, in which like reference characters designate like parts. In the drawings:—

Figure 1 is a side elevation of the front portion of the truck, showing the power-operated means for elevating the ladder thereon;

Fig. 2, a plan view of the cylinders containing the spring-operated pistons which actuate the ladder-raising means, and also showing the ladder-lowering screw;

Fig. 3, an enlarged, detail view of the ladder-lowering screw showing my improved controlling-mechanism as applied thereto; and

Fig. 4, a sectional, detail view of the locking-device for the ladder-operating mechanism.

Referring first to Fig. 1, 2 designates the fore part of the horizontal frame of the ladder-truck which is mounted on suitable running gear as usually provided, but not herein shown or described. Rotatably mounted on the top of the frame 2 is a revolving turntable 3 which supports the ladder 4 to adapt it to be turned in different directions as required. The supports for the ladder 4 consist of upright side-frames or brackets 5 having their legs fastened to the top of the turntable 3 and carrying a horizontal cross-shaft 6 at the top. The heel of the ladder 4 is pivoted on the cross-shaft 6 and a brake-drum 7, secured to one of its sides, is engaged by internal shoes, not here

shown, controlled by a hand-lever 8 on one of the side-frames 5. Secured to the sides or legs of the ladder 4 at the right of the pivot-shaft 6 are two V-shaped struts or braces 9 extending downwardly beneath the shaft and serving as the means for raising the ladder as later described.

Referring now to Fig. 2, two parallel, horizontal cylinders 10 are mounted fast on the top of the turntable 3, between the side-frames 5, and within them are slidable pistons 11. The pistons 11 are operated by compression-springs 12, two or more being employed in each cylinder, with one coiled within another as shown. The outer end of the pistons 11 are connected by a cross-rod or shaft 13 on the extremities of which are carried links or connecting-rods 14. The opposite ends of the links 14 are pivotally connected to the lower, apex ends of the side-braces 9, see Fig. 1. It will therefore be seen that when the springs 12 act to slide the pistons 11 outwardly in the cylinders 10, their connection through the links 14 with the struts or braces 9 will cause the ladder 4 to be tilted upwardly on its pivot-shaft 6 in the well known manner as usually provided in apparatus of this type.

For lowering the ladder into depressed relation with the frame 2 of the truck I employ a horizontal screw-shaft or worm 15 which is rotatably mounted in bearings 16, 17 on the turntable 3 between the cylinders 10. Fitted to engage the threads of the screw 15 is a sliding nut or sleeve 18, see Fig. 3, provided on its opposite sides with trunnions 19. Connected to the trunnions 19 are two parallel, horizontal rods or links 20 joined at their outer ends to the cross-rod 13 which extends between the pistons 11. As the pistons 11 are forced outwardly to raise the ladder 4 the links 20 will cause the nut 18 to slide on the screw 15 while rotating the latter in its bearings 16, 17. In lowering the ladder the screw 15 is turned manually to slide the nut 18 in the opposite direction, thereby retracting the pistons 11 and compressing the springs 12 to energize them for the next operation of raising the ladder. The screw 15 is rotated manually through the means of cranks 21 carried at the outer ends of two short shafts 22 at the front of the truck. The shafts 22 are journaled in bearings on suitable brackets 23.

projecting from the turntable 3 and carry bevel gears 24 at their inner ends adapted to mesh with a gear 25 on the screw 15. The gears 24 are maintained free from engagement with the screw-gear 25 during the elevation of the ladder, but are adapted to be meshed therewith by sliding the shafts 22 in their bearings.

The above described arrangement of the ladder-elevating and lowering mechanism is similar in construction to apparatus already in use and my improved controlling-means is applied thereto as next explained: Bolted to the top of the sliding nut 18, or formed as a part thereof, if preferred, is a block or bearing 26 in which is secured the end of a horizontally-extending square bar or rod 27, see Fig. 3. Preferably, the rod 27 is reduced in diameter and inserted through a bore 28 in the bearing 26 with its shoulder 29 abutting the forward side thereof. A nut 30 screwed onto the end of the rod 27 holds it rigidly in place in the bearing 26, or it might be secured thereto by any other convenient means. The opposite or forward end of the rod 27 is fitted to slide in a slotted bearing 31 constructed as a part of or attached to the end-bearing 17 of the screw 15. A cap 32 bolted to the top of the bearing 31 holds the rod 27 in place in its slot 33 while allowing it to slide therethrough, but it is to be understood that this detail of construction is not important and can be varied as preferred. On the side of the bearing 31 is a hub or boss 34 into which is screwed the end of a threaded shaft 35 carrying a hand-wheel 36 at its outer end, see Figs. 1 and 2. The end of the shaft 35 is adapted to be set against the flat side of the longitudinal rod 27 to bind the latter in its bearings and prevent movement of the sliding nut 18, when it is desired to lock the ladder in its raised position. To provide for positively locking the ladder in its lowered position against the action of the springs 12, a slot or socket 37 is formed in the side of the rod 27 with which the end of the shaft 35 engages as shown in Fig. 4. The operation of the complete device is as follows:

With the ladder 4 in lowered position, as illustrated in Fig. 1, the shaft 35 is screwed clear into its bearing in the hub 34 until its end seats in the socket 37 on the side of the rod 27. The rod 27 will thereby be held positively against longitudinal movement in the bearing 31 so as that the nut 18 is prevented from sliding on the screw 15. In this way the pistons 11 are held in their retracted position to maintain the ladder-elevating mechanism inactive until its operation is required. When it is desired to raise the ladder 4 the lock on the rod 27 is released by simply unscrewing the shaft 35 by means of the hand-wheel 36. The springs

12 will then act on the pistons 11, causing the links 14 to pull on the braces 9 to swing the ladder upwardly, as before described. During the raising of the ladder the operator manipulates the lever 8 to control the mechanism which acts on the brake-drum 7 to prevent a too sudden or rapid movement of the elevating-means. Then, when the ladder reaches the position desired, the hand wheel 36 is turned to set the shaft 35 against the sliding rod 27, and in this manner the ladder is held securely in place. It will be seen that my improved device provides a single means for securing the ladder in any position to which it is raised, and also a positive lock for holding the ladder in lowered position when not in use. The "down" lock is absolutely positive and proof against accidental release while the means for holding the ladder raised is also equally secure and reliable. At the same time the mechanism is so simple as to be proof against derangement or getting out of order while also being especially easy and convenient to operate since the hand-wheel 36 is accessible to an operator standing on the ground at the side of the truck.

Various modifications might be made in the construction and arrangement of the elements of my improved device without departing from the spirit or scope of the invention; therefore, without limiting myself to the exact embodiment shown, what I claim is:—

1. In an aerial-ladder truck, the combination with the frame thereof, of a ladder pivotally mounted thereon, power-operated means for lifting the ladder on its pivot, a stationary bearing mounted on the frame centrally beneath the ladder, a rod slidably axially in said bearing and connected to be moved by the means for raising and lowering the ladder, and means to grip said rod to lock the ladder in raised or lowered position.

2. In an aerial-ladder truck, the combination with the frame thereof, of a ladder pivotally mounted thereon, power-actuated means for elevating the ladder on its pivot, a rod slidably mounted for axial movement in a fixed bearing and connected to the ladder to be moved simultaneously therewith, and manually-operable means for gripping the rod in its bearing to lock the ladder in its raised or lowered position.

3. In an aerial-ladder truck, the combination with the frame thereof, of a ladder pivotally mounted thereon, power-operated means for elevating the ladder on its pivot, a rod mounted to slide in an axial direction in a fixed bearing and connected to the ladder to be moved simultaneously therewith, a screw-shaft in said bearing arranged to bind against the slidable rod, and a hand-wheel for turning the shaft to hold the rod from

sliding to lock the ladder in raised or lowered position.

4. In an aerial-ladder truck, the combination with the frame thereof, of a turntable 5 rotatably mounted thereon, a ladder pivotally supported at its heel on the turntable, power-operated means on the turntable for elevating the ladder on its pivot, a horizontal rod axially slidable in a fixed bearing on 10 the turntable and connected to move simultaneously with the ladder, a shaft threaded through the side of the bearing to bind against the rod, and a hand-wheel on the end of the shaft overhanging the side of the 15 truck-frame.
5. In an aerial-ladder truck, the combination with the frame thereof, of a ladder pivotally mounted thereon, power-operated means for elevating the ladder on its pivot, 20 a manually-rotatable screw, a sliding nut engaging the screw and connected to the ladder to lower it against the action of the elevating-means, a rod connected with the nut and slidable through a fixed bearing, and 25 means on the bearing for clamping the rod

therein to lock the ladder in raised or lowered position.

6. In an aerial-ladder truck, the combination with the frame thereof, of a turntable 30 rotatably mounted thereon, a ladder pivotally supported at its heel on the turntable, cylinders on the turntable, compression-springs in said cylinders, pistons slidable in 35 the cylinders under the action of the springs, a cross-rod connecting the ends of the pistons, braces depending from the sides of the ladder, links connecting the ends of the braces with the piston cross-rod, a screw mounted on the turntable between the cylinders, manually-operable means for turning 40 the screw, a nut slidable on the screw and connected to the piston cross-rod to compress the springs to lower the ladder, a rod connected with the nut and slidable through a 45 fixed bearing, and means to clamp the rod in its bearing to lock the ladder in raised or lowered position.

In testimony whereof I affix my signature.

EDGAR A. WHITAKER.
